UNITED STATES PATENT OFFICE.

WILLIAM E. HUGHES, OF MINERAL RIDGE, OHIO.

RAILROAD-TRACK CONSTRUCTION.

No. 866,470.

Specification of Letters Patent.

Patented Sept. 17, 1907.

Application filed February 26, 1907. Serial No. 359,344.

To all whom it may concern:

Be it known that I, WILLIAM E. HUGHES, a citizen of the United States, residing at Mineral Ridge, in the county of Trumbull and State of Ohio, have invented 5 new and useful Improvements in Railroad-Track Constructions, of which the following is a specification.

The invention relates to an improvement in railroad track constructions, and consists primarily in a metallic foundation for the rails.

10 The main object of the present invention resides in the production of longitudinal sleepers connected at suitable intervals by cross ties, forming a metallic base designed to be embedded in the road-bed ballast and firmly support the rails, the construction including a 15 means for adjustably connecting the rails to the longitudinal sleepers to permit necessary gage adjustment of the rails without interfering with the metallic foundation.

20 The invention will be described in the following specification, reference being had particularly to the accompanying drawings, in which:—

25 Figure 1 is a view in plan showing a portion of the metallic foundation for the rails, the rails being shown in position thereon, Fig. 2 is a section on line 2—2 of Fig. 1, Fig. 3 is a section on line 3—3 of Fig. 1, Fig. 4 is a perspective detail of the angle plates for securing the sleepers and ties together, Fig. 5 is a perspective of the base plates for connecting the sleepers and ties at their juncture with each other, Fig. 6 is a perspective view 30 of the rail securing plate for adjustably securing the rails to the sleepers.

Referring particularly to the accompanying drawings, wherein is shown the preferred embodiment of the present invention, my improved foundation comprises 35 essentially sleepers 1 and cross ties 2, the sleepers being arranged in parallel relation longitudinally of the road-bed, and the ties arranged transverse said road-bed and connected to the sleepers.

40 The ties and sleepers are preferably of identical construction, each being in the form of I beams, with the webs 3 and head flanges 4 of the sleepers of comparatively thicker material than the webs 5 and head flanges 6 of the cross ties. The head flanges 4 of the sleepers are also of greater transverse extent than the head flanges 6 of the cross ties, the increased dimensions 45 of the sleepers being essential in that they form the main rail supports.

50 The ties are disposed intermediate the proximate ends of the successive sleepers, and are preferably of greater length than the distance between the relatively outer edges of the sleepers when in proper position. The sleepers and ties are secured in connected position by angle plates 7, of approximately angular formation, one section of which is designed to bear against the web

of the cross tie between the head flanges thereof, and 55 the other section arranged to bear against the adjacent web portion of the sleeper. Each sleeper is connected to the adjacent tie by two such angle plates, arranged on opposite sides of the sleeper web and secured to the web portions of the tie. The angle plates are to be secured to the respective webs of the sleepers and ties by any desired form of connection, though for the particular purposes of this invention I prefer to use ordinary bolts 8.

The head flanges 4 and 6 of the respective sleepers 65 and ties are further connected on their relatively lower surfaces by bed plates 9 which are of materially greater length than the width of the head flange of the cross tie, and underlie the adjacent sleepers on opposite sides 70 of said tie. The plates 9 are practically co-extensive in width with the width of the head flanges 4 of the sleepers, and are provided adjacent each end with side flanges 10 designed when the plates are in place to be bent upward to overlie the side edges of the lower head flanges of the sleeper. In alinement with the 75 cross ties the plates 9 are provided with laterally projecting sections 11, designed to bear beneath the cross ties, and formed with side flanges 12 to embrace the edges of the flanges 6 of the ties. By the use of the bed plate 9, which is to be of such length as to extend some 80 distance on each side of the respective cross ties, the juncture between the ties and sleepers is further supported and disconnection of these parts under the weight of strains is effectively prevented.

The rails 13 are secured to the sleepers 1 through the 85 medium of securing plates 14, illustrated more particularly in Fig. 6. These plates comprise body portions 15 to underlie the base flanges of the rails, and tongues 16 and 17 projecting centrally from the opposing side edges of the body portion. The tongues are 90 of materially less width than the width of the body portion and are each formed with longitudinally arranged slots 18, as shown. The side edge of the body portion at each side of the tongues 17 is formed with upturned lips 19 designed to engage the base flange 95 of the rail.

The rails are secured in applied position on the sleepers through the medium of plates 14, said plates underlying the rails with the tongues 19 engaging the base flange on one side thereof. The plates are secured 100 to the head flange 4 of the sleeper through the medium of bolts 20 passed through said flange on opposite sides of the rail and entering the slots 18 in the securing plate. Through the medium of the slots it is obvious that the rails may be adjusted to any desired gage, as said plates 105 are movable transversely of the sleepers to permit such adjustment of the rails. The plates 14 are preferably arranged in alternate order, that is the lips 19 of one

plate will engage the base flange of the rail on one side of the web, while the succeeding plate will engage the base flange of the rail on the opposite side of the web, thereby preventing lateral movement of the rail in either direction after application of the securing plates.

It will be particularly noted that with the sleepers and ties embedded in the road-bed any spreading or independent movement of said sleepers and ties is absolutely prevented. Furthermore, the juncture of the 10 sleepers and ties is secured to an underlying bed-plate by which separation at their juncture is absolutely prevented.

It is to be understood that the sleepers are to be of the particular length found necessary for the specific purposes of the railroad under construction, as in light travel fewer cross ties are necessary than in heavy travel. The construction provides a solid rail foundation of all metallic parts, thereby materially facilitating the proper maintenance of the road-bed and preventing any yielding of the rail through lack of proper support.

The spacing of the securing plates provides for unsupported intervals of the rail proper, whereby a certain degree of resiliency is permitted the rail and the 25 rigid connection heretofore objectionable in metallic foundations is entirely avoided.

Having thus described the invention what is claimed as new, is:—

1. A railroad foundation comprising sleepers, means for 30 securing the tracks thereto, cross ties connecting the ends

of the sleepers, means for reinforcing the connection between said ties and sleepers, and bed-plates underlying the juncture of the ties and sleepers.

2. A railroad foundation comprising longitudinally arranged sleepers, cross ties disposed intermediate the ends 35 of the sleepers, means for connecting said ties to the respective sleepers, bed-plates underlying the juncture of the ties and sleepers, and rail securing plates secured to the sleepers.

3. A railroad foundation comprising longitudinally arranged sleepers, cross ties disposed intermediate the ends 40 of the sleepers, means for connecting said ties to the respective sleepers, bed-plates underlying the juncture of the ties and sleepers, and rail securing plates adjustably secured to the sleepers. 45

4. A railroad foundation comprising sleepers, ties arranged transverse the ends of the sleepers, angle plates connecting the proximate surfaces of the sleepers and ties, bed-plates underlying the juncture of the sleepers and ties, means for securing said bed-plates to the respective sleepers and ties, and rail securing plates adjustably mounted on the sleepers. 50

5. A railroad foundation comprising sleepers, ties arranged transverse the ends of the sleepers, angle plates connecting the proximate surfaces of the sleepers and ties, bed-plates underlying the juncture of the sleepers and ties, means for securing said bed-plates to the respective sleepers and ties, and rail securing plates adjustably mounted on the sleepers, said rail securing plates being formed with upturned lips to engage the base 60 flanges of the rails. 65

In testimony whereof, I affix my signature in presence of two witnesses.

WILLIAM E. HUGHES.
